UNITED STATES PATENT OFFICE.

PATRICK MACK CANTY, OF ALTOONA, PENNSYLVANIA.

FLUE-EXTRACTOR.

1,343,431.

Specification of Letters Patent. Patented June 15, 1920.

Application filed September 23, 1919. Serial No. 325,794.

To all whom it may concern:

Be it known that I, PATRICK MACK CANTY, a citizen of the United States, and a resident of Altoona, in the county of Blair and State of Pennsylvania, have invented 5 certain new and useful Improvements in Flue-Extractors, of which the following is a specification.

My invention relates to flue extractors. 10 An important object of my invention is to provide a flue extractor which will so effectively and powerfully engage the flue that the enormous pulling force necessary to withdraw the flue may be applied.

Another important object is to provide a 15 flue extractor with guiding means for the gripping elements thereof which will constrain the gripping elements to move in such manner and to such positions as to be most effective to the end of securely gripping the flue.

Another important object is to provide 20 means for positively withdrawing the gripping elements from engagement with the flue when desired.

Another object is to provide gripping 25 elements of strong, substantial and durable structure capable of withstanding all of the severe stresses incident to their uses and 30 adapted to have their gripping portions ground or sharpened to give said gripping portions the requisite cutting edge.

Another object is to provide retaining 35 means which will permit the requisite movement and operation of the gripping elements but which will retain these elements in associated relation.

Other objects and advantages reside in cer- 40 tain novel features of the construction, ar- rangement and combination of parts and will become apparent as the description pro- 45 ceeds, reference being had to the accom- panying drawings forming part of this speci- fication, and in which:—

Figure 1 is a side elevational view,

Fig. 2 is a side elevational view showing a modified form of retaining means,

Fig. 3 is a sectional view taken on line 3—3 of Fig. 2,

Fig. 4 is an elevational view, the means for withdrawing the gripping elements being omitted,

Fig. 5 is an elevational view of one end, 55 Fig. 6 is a sectional view on line 6—6 of Fig. 4, and

Fig. 7 is an elevational view of the opposite end from Fig. 5.

Referring to the drawings, it will be seen 60 my invention includes means for engaging or gripping the flue, comprising a spool-like structure consisting of a plurality of sections, segmental in cross section and preferably three in number. Each section comprises a hub portion 10 having integral flanges 11 at each end thereof. These flanges have their surfaces tapering to form peripheral cutting edges 12 adapted to bite into the wall of the flue as hereinafter more full described. The flanges are of substantial cross section adjacent the hub portion and have their inner surface tapering gradually and their outer surface tapering more abruptly, as shown in the drawing. In this manner, the peripheral cutting edges 12 are so formed that they may be readily ground or sharpened to give and preserve the requisite edge and at the same time the flanges 11 are of such a strong and durable construction 65 that they are capable of withstanding all of the severe stresses imposed upon them. 70

The retaining and guiding means preferably comprises annular plates 13 provided with radial slots 14 and central apertures 15. These plates are arranged adjacent each of the ends of the gripping means, as shown in 75 Figs. 1 and 4, the radial slots being adapted to receive the pins 16, secured at their inner ends to the sections of the gripping means and provided at their outer ends with heads 16' to constrain the pins and the grippers 80 against any except radial movement relative to the plates 13. The central aperture 15 is formed to accommodate the expanding means to be hereinafter more fully described. 85

The means for expanding the gripping elements comprises a tapered bar or shaft 17 which is mounted for slidble movement between the segmental sections or gripping elements of the gripping means and through the apertures of the guide plates. The shaft is provided at its smaller end with an integral eye 18, to which power from any suitable source may be applied to effect longi- 95

tudinal sliding movement of the tapered bar or shaft and a resultant outward radial movement of the gripping elements.

It is to be noted that the guide plates 13 serve not only to guide the gripping elements, as hereinbefore described, but also serve to maintain these gripping elements in proper associated relation and to prevent any serious displacement of these elements relative to each other. If desirable, the guiding means may be omitted and a modified form of retaining means may be employed, as shown in Fig. 2. This retaining means comprises a retaining band 19 which encircles the hub portion of the gripping elements and serves to prevent displacement of these elements with respect to each other.

The means for releasing or withdrawing the gripping elements from engagement with the flue comprises a conical boss in the form of sections 20, each of said sections being preferably integrally formed with a gripping element. These sections are spaced from each other when the gripping elements are expanded into engagement with the flue and when these sections are compressed or moved into contact with each other, forming the frusto-conical boss, they serve to withdraw the gripping elements from engagement with the flue. The means for compressing or moving the sections toward or into contact with each other consists of a release collar 21 slidably mounted on the shaft 17 and provided at the end adjacent the conical boss with a conical cavity 22, as shown in dotted lines in Figs. 1 and 2. The inclined walls of this conical cavity engage the inclined walls of the conical boss and serve to compress or move the sections toward each other or into contact with each other. The release collar is provided with a reduced extension 23 also slidably mounted on the shaft and having a central bore therein of such diameter as will give the release collar the required range of movement on the shaft 17. The reduced extension is provided with a plurality of radial threaded bores adapted to receive set screws 24 which may be moved to engage the shaft and thereby lock the release collar in the desired position on the shaft.

In practice, the device is inserted in the flue to be withdrawn with the gripping elements in contracted position and preferably arranged adjacent the smaller end of the tapered boss or shaft. The power is then applied from any suitable source through any suitable means to the eye 18 of the tapered boss to move the same longitudinally through the gripping elements. This action serves to expand the gripping elements and expand them radially by virtue of the engagement of the pins in the radial slots of the guide plates until the cutting edges 12 of the gripping elements securely bite into

the walls of the flue. By virtue of the particular form of the flanges constituting the gripping elements or jaws, the cutting edges bite into the flue only enough to securely engage with the same and do not serve to completely penetrate or pierce the structure of the flue. The power subsequently applied to the eye 18 serves to withdraw the flue. It is to be noted that the space interval between the gripping elements or jaws give the same a wide range of action, and the relatively large extent of bearing surface provided between the gripping sections and the expanding shaft results in the proper disposition of the gripping sections and the transmission of adequate gripping and pulling action to said sections.

I claim:

1. A flue extractor comprising gripping means consisting of a plurality of sections each section including a hub portion and gripping jaws formed on each end of said hub portion, guide pins secured to each of said gripping jaws, annular guide plates arranged adjacent said gripping jaws and provided with radial slots adapted to receive said guide pins to constrain said gripping jaws to radial movement, a tapered shaft for expanding said gripping jaws into engagement with the walls of the flue, frusto-conical sections formed on each of said gripping jaws adapted when said gripping jaws are contracted to contact with each other to form a frusto-conical boss, and a release collar having a frusto-conical cavity, the inclined walls of which are adapted to bear against the inclined walls of said conical sections to move same into contact with each other to contract said jaws, said release collar having a reduced extension and radial set screws therein, adapted to set said release collar in the desired position on said shaft.

2. A flue extractor comprising gripping means consisting of a plurality of sections each section including a hub portion and gripping jaws formed on each end of said hub portion, guide pins secured to each of said gripping jaws, annular guide plates arranged adjacent said gripping jaws and provided with radial slots adapted to receive said guide pins to constrain said gripping jaws to radial movement, a tapered shaft for expanding said gripping jaws into engagement with the walls of the flue, frusto-conical sections formed on each of said gripping jaws adapted when said gripping jaws are contracted to contact with each other to form a frusto-conical boss, and a release collar having a frusto-conical cavity, the inclined walls of which are adapted to bear against the inclined walls of said conical sections to move the same into contact with each other to contract said jaws.

3. A flue extractor comprising gripping means consisting of a plurality of sections,

each section including a hub portion and gripping jaws formed on each end of said hub portion, guide pins secured to each of said gripping jaws, annular guide plates 5 arranged adjacent said gripping jaws and provided with radial slots adapted to receive said guide pins to constrain said gripping jaws to radial movement, a tapered shaft for expanding said gripping jaws 0 into engagement with the walls of said flue, and means including a slidible member on said tapered shaft adapted to contract said jaws and thereby withdraw them from engagement with the flue.

5. A flue extractor comprising gripping means consisting of a plurality of sections, each section including a hub portion and gripping jaws formed on each end of said hub portion, guide pins secured to each of 10 said jaws, annular guide plates arranged adjacent said gripping jaws and provided with radial slots adapted to receive said guide pins to constrain said gripping jaws to radial movement, and a tapered shaft for 15 expanding said gripping jaws into engagement with the walls of said flue.

5. A flue extractor comprising gripping means for engaging the flue, guiding and retaining means for said gripping means 30 consisting of annular plates having slots therein, and pins secured to said gripping means and slidable in said slots.

6. A flue extractor comprising gripping means for engaging the flue, guiding and 35 retaining means adapted to constrain said gripping means to radial movement, consisting of annular plates having radial slots therein, and pins secured to said gripping means and radially slidable in said slots.

40 7. A flue extractor comprising gripping means consisting of a plurality of sections, each section including a hub portion, and gripping jaws formed on each end of said hub portion.

45 8. A flue extractor comprising gripping means consisting of a plurality of sections, each section including a hub portion, and flanges constituting gripping jaws formed on each end of said hub portion, said 50 flanges having their inner surface tapering gradually and their outer surface tapering abruptly to form peripheral cutting edges, substantially as described.

9. A flue extractor comprising gripping 55 means consisting of a plurality of sections, each section including a hub portion and gripping jaws formed on each end of said hub portion, and means for expanding said sections to force the gripping jaws into engagement with the walls of the flue.

60 10. A flue extractor comprising gripping means for engaging the flue, guiding and retaining means for said gripping means, expanding means associated with said gripping means adapted to force said gripping 65

means into gripping engagement with the walls of the flue, and means adapted to positively withdraw said gripping means from engagement with the walls of the flue.

11. A flue extractor comprising gripping 70 means for engaging the flue, and means adapted to positively withdraw said gripping means from engagement with the walls of the flue.

12. A flue extractor comprising gripping 75 means adapted to be expanded to engage the flue, expanding means associated with said gripping means adapted to force said gripping means into gripping engagement with said flue, release means associated with 80 said gripping means, and actuating means adapted to operate said release means to withdraw the gripping means from engagement with the flue.

13. A flue extractor comprising gripping 85 means including a plurality of gripping elements adapted to be expanded to engage the flue, expanding means associated with said gripping means adapted to force said gripping elements into engagement with said flue, a conical release boss formed of a plurality of sections, each of said sections being secured to a gripping element, and said sections being spaced from each other when the gripping elements are expanded 90 into gripping engagement with the flue, and a release collar having a conical cavity the walls of which are adapted to engage the spaced sections of said conical boss to force said sections together and thereby withdraw the gripping elements from engagement 95 with the flue.

14. A flue extractor comprising gripping 100 means including a plurality of gripping elements adapted to be expanded to engage the flue, expanding means associated with said gripping means adapted to force said gripping elements into engagement with said flue, a conical release boss formed of a plurality of sections each of said sections 105 being secured to a gripping element, and said sections being spaced from each other when the gripping elements are expanded into gripping engagement with the flue, and means for forcing said sections together to 110 withdraw the gripping elements from engagement with the flue.

15. A flue extractor comprising gripping 115 means for engaging the flue, expanding means associated with said gripping means 120 adapted to force said gripping means into gripping engagement with the walls of the flue, and means adapted to positively withdraw said gripping means from engagement with the walls of the flue.

16. A flue extractor comprising gripping 125 means consisting of a plurality of sections, each section including a hub portion and gripping jaws formed on each end of said hub portion, and means constraining said 130

sections to substantially operative movement to engage the flue and to release the same, respectively.

17. A flue extractor comprising gripping means consisting of a plurality of sections, each section including a hub portion, and flanges constituting gripping jaws formed on each end of said hub portion, said flanges

having their inner surfaces tapering gradually and their outer surfaces tapering abruptly to form peripheral cutting edges, and means constraining said sections to substantially operative movement to engage the flue and release the same, respectively, substantially as described.

PATRICK MACK CANTY.
